TUBE ROLLING MILL

William John Norton, Salford, England, assignor
to Sir James Farmer Norton & Company Limited,
Salford, England, a British company

Application December 24, 1935, Serial No. 56,099
In Great Britain December 21, 1934

8 Claims. (Cl. 80—14)

This invention relates to mills for rolling tubes in order to reduce the metal thickness and if desired the bore of the tube, the mill being of the type in which the tube upon a mandrel is alternately gripped and released by the dies or rolls which rotate in one direction only and which grip and swage or reduce the tube during part only, say one half of each revolution, the tube and mandrel being traversed in one direction during the swaging operation and being returned when the dies or rolls cease to grip the tube, an increment of feed and a partial turn being imparted to the tube during each return movement.

10 The object of my present invention is to provide improvements in the said type of mill which facilitate and expedite the production of the reduced tubes.

15 In accordance with my invention, the mandrel is reciprocated through a definite path and does not advance through the dies or rolls with the tube being rolled or reduced. The tube alone has the increments of feed and turning movements imparted thereto and is freed from the mandrel at each cycle of operations.

20 The dies or rolls act to swage the tube during less than 180°, preferably not more than 120° of each revolution of the dies and the carriage or slide by which the mandrel and tube are reciprocated is actuated by a crank, connecting rod and a bell crank lever running in part in a cam track so as to compensate for the varying angularity of the crank and to give to the carriage or slide a rate of movement substantially the same as that resulting from the surface engagement of the swages and tube during the swaging stroke. The extension of the tube due to its reduction by the swages results in an advance through the dies.

25 The invention therefore comprises the improved combinations and arrangements of parts as hereinafter described and claimed.

30 Referring to the accompanying explanatory drawings:—

Figures 1, 2 and 3 taken together constitute a 35 side elevation of a machine constructed in one convenient form in accordance with this invention.

Figures 4, 5 and 6 taken together constitute a 40 plan view of the machine shown in Figures 1, 2 and 3.

45 Figures 7, 8 and 9 are detailed views of parts included in the remaining figures, which will be hereinafter referred to.

50 Figure 10 shows the relative positions of the swages and crank.

In Figures 1 and 4, upon the bed *a* of the machine is mounted for reciprocatory movements a slide *b* (see also Figure 8 which is a sectional view of the slide) to which is secured the rear end of a screw *c*, which can be termed the feed screw, and also a chuck or collet *d* for holding the rear end of a mandrel *e*. The feed screw *c* is adapted for intermittent rotary movement as hereinafter described and it turns a gear wheel *f* which meshes with a gear wheel *g* upon the sleeve *h* carrying the chuck or collet *d*. The slide *b* is reciprocated by the rod *i* to which it is adjustably secured by nuts *j* on the opposite sides of a lug *k* upon the slide through which the rod *i* passes.

55 The screw *c* can be given rotary movements by the electric motor *m* through the sprocket wheels *n* and a chain. There is an axially fixed ratchet wheel *p* through which the feed screw threads, the said ratchet wheel serving in conjunction with a pawl, not shown, to cause the screw to turn in a forward direction when the screw is being propelled forwards, that is towards the swages to be hereinafter referred to, but allowing the screw to move without turning when it is being propelled backwards.

60 Referring now to Figures 2 and 5, which show the middle section of the machine, the mandrel *e* passes through the chuck or collet *q* upon a slide *r* but is not engaged by such chuck or collet. The latter grips the tube *s* which is being reduced by the machine. The feed screw *c* threads through a part *t* in the slide *r* (see Figure 9) which acts as a nut with respect to the screw, reciprocatory movements of the screw causing corresponding reciprocatory movements of the nut and slide and a rotary movement of the screw imparting an additional movement to the slide along the bed *a*. A wheel *u* in the slide is feather keyed to the screw *c* so that it turns with the latter and such wheel gears with a wheel *v*, which is upon a sleeve *w* rigid with the collet *q* so that rotary movements of the wheel *v* cause rotary movements of the collet or chuck *q* and the tube *s*.

65 Referring now to Figures 3 and 6 which show the forward section of the machine, there are a pair of rotary dies or swages *10* and *11*, each made in two pairs and clamped upon and keyed to a driving shaft, the two shafts *12* and *13* being geared together and driven by a suitable motor (not shown). Upon the lower shaft *13* is a crank arm *14* with a crank pin *15* of adjustable throw therein. A connecting rod *16* upon said crank pin is coupled to the fulcrum of a bell crank lever *18* (see Figures 2, 5 and 7). The said fulcrum pin has two slides *19*, one at each

end of the pin, which run in straight slots 20 in a frame 21 connected to the machine base *a*. There are two rollers 22 on one end of the bell crank lever 18, which run in cam slots 23 in 5 the frame 21. The other end of the bell crank lever has a connecting rod 24 pivoted thereto, the said rod serving to reciprocate the rod *i* which is carried in brackets along one side of the machine base and which as already described 10 traverses the slide *b*, to which the ends of the mandrel *e* and feed screw *c* are secured. If the connecting rod 16 were connected directly to the rod *i*, the linear motion of the slide *b*, mandrel *e* and feed screw *c* would tend to be different from 15 the linear motion of the tube being swaged when the swages were driving the tube backwards towards the slide *b* during the actual swaging period, due to the varying angularity of the crank arm 14 as will be readily understood, but 20 by interposing the bell crank lever 18, the cam track 23 and the connecting rod 24 between the rod 16 and the rod *i*, it is possible to compensate for the varying angularity of the crank arm 14 and to give to the slide *b* a motion substantially 25 the same as the motion imparted to the tube by the swages as they roll thereon during swaging. It is however impossible to effect in a practical manner a correct compensation if the swages operate through an angle of more than about 30 120° so the swages as shown in Figure 10 are designed to operate upon the tube for an angular movement of the swages of about 120°; the remaining part of the surface of the swages is clear 35 of the tube. The crank arm 14 is so situated with relation to the leading edge of the swage which first engages the tube that it is approximately 30° from the horizontal plane containing the axis of the bottom swage and the path through which the axis of the fulcrum pin 17 40 travels in its slot 20. This disposition of the crank arm 14 provides that the compensation to be effected by the cam groove or slot 23 is a minimum as only the flatter part of the circle of movement of the crank pin 15 has to be dealt 45 with.

The rod *i* also reciprocates a slide 25 (see Figures 3 and 6) situated at the delivery side of the dies or swages, which carries a collet or chuck 26. The latter is opened and closed upon the 50 tube coming from the dies or swages by an inertia slide 27 which is coupled by links 28 to levers 29 operating the chuck jaws. The collet or chuck is adapted to be turned by gear wheels 30, 31, the latter of which is splined or feather 55 keyed upon the screw 32 which is turned by a nut 33, the exterior of which constitutes a ratchet wheel and is held against turning in one direction by pawls (not shown). It will be seen therefore that as the slide 25 reciprocates, the 60 collet or chuck 26 will be turned when the slide moves in one direction, which is to the right in the figures and does not turn when the slide moves in the other direction, that is to the left in the figures.

65 The inertia slide 27 acts as follows:—When the slide 25 moves to the right in Figure 3, the slide 27 lags and so causes the links 28 to turn the levers 29 and close the chuck jaws upon the tube within the chuck. The two slides then 70 move together carrying the tube with them. When the slide 25 moves to the left, the slide 27 lags and this time turns the levers 29 so that they release the chuck jaws. The two slides then 75 move together. The chuck 26 serves to draw the

reduced end of the tube positively forward and also prevents over-run of the tube. It also deals effectively with the reduced tube when its rear end has been released from the chuck *q* and is being propelled forward by the following tube. 5 In this case, the reduced tube might over-run when being propelled forward by the following tube.

The operation of the complete machine is as 10 follows:—

A tube is fed into the machine by releasing the chuck *d* and sliding the tube over the mandrel *e*. The chuck *d* is then closed on the mandrel again and the tube end is gripped in the chuck *q*. The mandrel end comes between the swages as shown 15 in Figures 3 and 10 at the start of each swaging stroke, the mandrel retreating during swaging due to the crank arm 14, crank pin 15, connecting rod 16, bell crank lever 17, connecting rod 24 and rod *i* which cause reciprocation of the slide *b*. On the forward stroke of the rod *i*, the mandrel *e* and tube *s* are turned through an angle which may be 90° by the action of the feed screw *c* which is turned by the ratchet wheel *p* and so imparts in addition to the reciprocatory movement a feed or forward motion to the slide *r* and so to the tube *s*. The latter enters between the swages and is alternately swaged and released. When released it is fed forward and turned, the mandrel however always reciprocating between the same limits and being turned on the forward stroke. In other words the tube gradually progresses over the mandrel. When the feed screw is moving in a backward direction, the ratchet wheel *p* turns with it so that the screw has no rotary motion. The tube end progresses towards and is finally engaged by the chuck 26 on its forward stroke until it has all 20 been swaged down and leaves the swages. When one tube has been swaged for the major portion of its length, its end is released from the chuck *q* and a further tube is fed along the mandrel and its outer end gripped in the chuck *q*. The latter is fed backwards along the machine base by rotating the motor *m* and freeing the ratchet wheel *p*. The motor can also be operated to feed the chuck *q* to a position in which the tube is about 25 to enter between the swages. 30

By reference to Figure 10, it will be seen that the swages which turn continuously in one direction, have a portion of their surface covering an angle of about 120° which performs the actual swaging and that whilst swaging is taking place the crank arm 14 is moving through an angle of 120° disposed equally at the opposite sides of a vertical plane containing the axis of the swages. When the swages are engaging the tube, they tend to push it back towards the feed end, and extrude the displaced metal forward towards the delivery end of the machine. This action of the swages might be utilized to drive the slides backwards, the rod *i* merely performing the forward propulsion, in which case the co-operating means (namely the bell crank lever 18 and associated parts) might be dispensed with, the rod *i* engaging the slides *b* and 25 at one side only. 35

The positions of the slides 2 and 25 can be adjusted with relation to the rod *i* by the nuts shown. 40

What I claim is:—

1. In a tube rolling mill, in combination, a base or bed, a slide movable along said bed, a chuck upon said slide to receive a mandrel, a feed screw secured to said slide, a second slide, 45

- a chuck upon said second slide to receive a tube around the mandrel, a fixed nut upon said second slide engaging the feed screw, means for turning the feed screw when it is traversed in one direction only, means upon the slides whereby the feed screw when turned turns the two chucks and imparts a feed movement to the second slide, a head containing two rotary swages, a third slide with a chuck thereon at the delivery side
- 5 6 of the swages to engage the reduced tube, means for turning said chuck in unison with the other chucks, means actuated in unison with the swages for reciprocating the three slides through definite distances, and means whereby the chuck
- 10 15 upon the third slide closes when that slide moves in a forward direction and opens when it moves in a reverse direction.
2. In the means claimed in claim 1, a crank arm rotated with one of the swages, a crank pin upon said arm, a connecting rod upon said pin, a bell crank lever, the fulcrum pin of which moves in a straight path and is coupled to the connecting rod, a cam track or groove turning the bell crank lever about its fulcrum as it is reciprocated by said connecting rod, a second connecting rod coupled to the bell crank lever, and a rod reciprocating the three slides coupled to said second connecting rod.
- 20 25 3. In the means claimed in claim 1, two swages having each a swaging surface covering an angle of about 120°, a crank arm rotated in unison with one swage and being at an angle of 30° in the rear of the leading edge of the said swage, and means compensating for the varying angularity 30 35 of the crank arm in transmitting reciprocatory motion to the slides.
4. In a tube rolling mill, in combination, a pair of swages rotating continuously in one direction only, a mandrel reciprocated from and to a definite point in relation to the swages, means for reciprocating the tube being swaged through 5 the same length of traverse as the mandrel upon which it is placed, means imparting increments of feed to the tube after each swaging operation as the tube moves towards the swages, and means turning both the tube and the mandrel after 10 each swaging operation as the tube and mandrel move towards the swages.
5. In a tube rolling mill as claimed in claim 4, providing the swages with a swaging surface extending around not more than 120° only of each 15 swage.
6. In a tube rolling mill as claimed in claim 4, means permitting movements of the tube and mandrel during the swaging operation under the action of the swages relatively to the means 20 which impart back or forth or reciprocatory movements to the tube and mandrel.
7. In a tube rolling mill as claimed in claim 1, means allowing of a limited amount of relative movement between the mandrel and its chuck 25 or chuck slide, means allowing of a limited amount of relative movement between the tube and its chuck slide and means reciprocating the mandrel slide through a definite path in unison with the swages.
8. In a tube rolling mill as claimed in claim 1, traversing the mandrel slide positively in one direction by crank and connecting rod in unison with the swages, and allowing the rolling action 30 35 of the swages to traverse it in other direction.

WILLIAM JOHN NORTON.
